UNITED STATES PATENT OFFICE.

WILLIAM HIGGINS, OF NEWARK, NEW JERSEY.

COMBINED SPANKER AND BREASTER FOR BOOT OR SHOE MAKING MACHINES.

SPECIFICATION forming part of Letters Patent No. 600,264, dated March 8, 1898.

Application filed April 17, 1897. Serial No. 632,587. (No model.)

To all whom it may concern:

Be it known that I, WILLIAM HIGGINS, a citizen of the United States, residing at Newark, in the county of Essex and State of New Jersey, have invented certain new and useful Improvements in a Combined Spanker and Breaster for Boot or Shoe Making Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to a novel construction of machines for attaching heel-sections to boots or shoes and trimming the same, said operations of the machine being termed, respectively, the "spanking" and "breasting" operations.

The primary object of this invention, therefore, is to provide a combined spanking and breasting mechanism for attaching and trimming heel-sections to boots or shoes, such attachment being employed, primarily, to "spank" the heel-section, which is placed by the operator upon the nails projecting from the heel portion made by other machinery and thereby attach said heel-section to the heel proper, and then, almost at the same instant, by the descent of a suitable cutter, "trimming off" or breasting that surface of the heel which is placed directly back of the sole of the boot or shoe.

With these ends in view the invention consists in the novel construction of a combined "spanker" and "breaster" for the purposes above stated; and also in novel arrangements and combinations of parts, as well as in the details of construction thereof, all of which will be fully set forth in the accompanying specification and finally embodied in the clauses of the claim.

The invention is clearly illustrated in the accompanying sheets of drawings, in which—

Figure 1 is a side elevation of a machine embodying the principles of my present invention. Fig. 2 is a front view, on an enlarged scale, of the combined spanker and breaster; and Fig. 3 is a longitudinal vertical

section taken on line 3 3 in said Fig. 2. Fig. 4 is a horizontal section taken on line 4 4 in Fig. 3. Fig. 5 is a part section and elevation of the operating parts of the machine, illustrating the spanker in its operated position while causing the attachment of the heel-section to the heel of the boot or shoe; and Fig. 6 is a similar view of the same parts, illustrating the trimmer or breaster in its operated position when the spanker is about to return to its initial position. Figs. 7 and 8 are detail views of a cam-action and guide for timing the movements of the spanker and breaster. Fig. 9 is a perspective view of a combined cam sleeve and clutch secured upon the main driving-shaft for throwing in and out the operating mechanism of the machine, and Fig. 10 is a general perspective of the several parts comprising the combined spanker and breaster before they are assembled and operatively secured together.

Similar letters of reference are employed in all of said views to indicate corresponding parts.

In said drawings, A indicates the main frame of the machine, which can be secured upon a suitable table b, having legs or supports b', substantially as illustrated in Fig. 1. The said main frame A of the machine is provided at its upper end with a suitable bearing portion a and a bearing-plate a', which is secured upon said portion a by means of bolts or screws a² to form a bearing for the main operating-shaft c, which is provided with pulley-wheel c' at one end for operating said shaft. The hub c² of said wheel c' is cut away, as at c³, and upon said shaft, adapted to slide in the space between the bearing of the standard A and said hub c², is a clutch collar or sleeve d, having a projection or finger d', which is in normal holding engagement with the slot c³ in said wheel c', when an actuating rod or bar e has its end e' withdrawn from a pair of cam-shaped projections d², forming a guide on said sleeve d. Said rod or bar e, which is operatively arranged in certain bearing portions in a pair of arms a³ and a⁴, extending from the back of the standard and has a spring g arranged between said arms a³ and a⁴ and encircles said rod, extends down through an opening in said standard A and

the table b , and is pivotally connected by means of a pin or bolt e^2 with a foot-lever e^3 , fulcrumed at e^4 to a suitable bearing e^5 , substantially as illustrated. The normal tendency of said spring g is to force said rod or bar e upward and bring the end e' of said bar to the position illustrated in Fig. 6, and when the projections d^2 on said clutch-sleeve d are brought around to the position illustrated in Fig. 1, then the cam-surfaces of said projections will slide against a correspondingly-formed surface on said end piece e' of the rod e , whereby the clutch-sleeve will slide laterally on the shaft c , which throws the breaster mechanism out of operation. Said clutch-collar d will thus be thrown out of gear with the wheel c' as long as the operator does not depress the foot-lever e^3 , but when said lever is forced down then the end e' of the rod e will be withdrawn from its operative engagement with the clutch-collar d and a suitable spring d^3 , encircling the shaft c , will immediately cause operative contact between said clutch-collar and the wheel c' , as will be clearly evident.

As will be seen from Figs. 3, 5, and 6, the forward portions of the bearing-part a and the plate a' are enlarged, as at a^5 and a^6 , respectively, and rotatively arranged in said enlarged portions a^5 and a^6 is a disk-like part c^4 , connected with the main shaft c , said disk-like part c^4 being provided with an outwardly-extending stud or pin c^5 , forming a crank-wrist, substantially as illustrated. Secured to the two ends of the said portions a^5 and a^6 and against the front thereof by means of suitable bolts f^2 are a pair of guides f and f' , provided with V-shaped or other suitably-shaped guiding surfaces or ways f^3 , as clearly illustrated in Fig. 8. Adapted to slide up and down between said guides f and f' is the spanker, consisting, essentially, of a rectangular plate h , having V-shaped or other suitable guiding portions h' , which fit into the correspondingly-formed ways f^3 of the guides f and f' , and with an opening h^2 , in which is loosely fitted and capable of a lateral sliding motion therein a plate i , having an opening i' , bounded by eccentrically-arranged curves i^2 , i^3 , and i^4 , whereby a yoke is provided working upon said crank-wrist c^5 , hereinabove mentioned, as will be clearly evident from Figs. 3, 5, 6, and 7. Thus it will be seen that when the pulley-wheel c' operates the shaft c said wrist-pin c^5 will act against the cam or eccentric surfaces i^2 , i^3 , and i^4 of the yoke i , causing a vibratory motion of the spanker-plate h .

As will be seen from Figs. 1, 2, and 3, on the table b of the machine I have secured a plate j , having guide-bars j' , and adapted to slide between said bars on the plate j is a second plate k , having an arm k' , provided with a bearing portion k^2 , having a smooth bore and a slot k^3 , as clearly shown in Fig. 2. Beneath said bearing portion k^2 is a sleeve

k^4 , having an internal screw and holes k^5 or other suitable means for turning said sleeve, to cause the raising or lowering of a hub k^6 in said sleeve k^4 . To prevent the turning of said hub k^6 when said sleeve k^4 is turned, said hub k^6 has a slight projection or pin k^7 , which extends into said slot k^3 in the bearing portion k^2 . The operation of these parts will be clearly understood from an inspection of said Fig. 2. It will also be seen from said Fig. 2 that said hub k^6 is provided with a chamber k^8 and a slight projection k^9 . In said chamber k^8 is a spring m of suitable resilience, and resting upon said spring is a jack n , provided with a longitudinal slot or groove n' , into which said projection k^9 extends to return said jack at all times in its proper position. The standard A of the machine is provided with a suitable bracket a^7 , having a bearing a^8 and a spring-actuated adjusting-screw a^9 in said bearing, said screw being provided with a holder a^{10} , made of spring metal, which is arranged directly above the support n^2 of the jack n and consists, essentially, of a pair of spring-arms a^{11} , between which the heel portion of the unfinished boot or shoe is forced and held in its proper position ready for spanking the heel-section upon the heel as the spanker moves down upon the same, as clearly indicated more especially in Fig. 1.

To return to the construction of the spanker, said plate h is provided on the front with a pair of guide-bars h^3 , having grooves or ways h^4 , in which are loosely arranged the vertical guides l and l' of a breaster-plate l , provided with a pair of perforated ears or lugs l^3 and a pair of outwardly-extending and screw-threaded lugs l^4 , into which are screwed a pair of adjusting-screws l^5 . In said perforated ears or lugs l^3 I have secured a bolt or pin o and a link o' , connected therewith, the other end of said link being attached to a pin o^2 , secured in a pair of perforated ears or lugs p' of a block p , which is secured by means of a bolt or screw p^2 , encircled by a spring p^3 in the socketed end r' of a lever r , fulcrumed at r^2 in a bearing s , securely attached to the top of the frame of the machine. A spring r^3 is attached at or near the said socketed end r' to the said lever and also to a frame t , secured to the guide-bars f and f' or to any other suitable part of the machine, which spring causes said lever r to assume the position indicated in the several figures of the drawings, with a roller or wheel r^4 in the opposite end of said lever in constant rolling engagement with the sleeve d on the shaft c and at times with a suitable cam projection d^4 on said sleeve, for the purposes to be more fully set forth hereinafter.

As will be seen from Figs. 1, 2, and 10, the breaster-plate l , hereinabove mentioned, has a pair of holes l^6 , and adjustably arranged between a pair of projections l^7 on said plate is a knife or cutter u , having a pair of slotted holes u' , through which the bolts u^2 are passed

and screwed into the holes l^6 in said plate l , for adjustably securing the knife or cutter u to said plate. The lower cutting portion u^3 of said knife is suitably curved to conform 5 with the shape of the back surface of the heel to be trimmed. Upon the face of the knife or cutter u is lug u^4 for receiving the screw-threaded end u^6 of a stop-bar u^5 , having a flattened and comparatively broad end u^7 , which is brought down upon the sole of the shoe directly in front of the heel, and if properly adjusted in said lug u^4 will regulate the downward sliding motion of the knife or cutter and the breaster-bar and prevents the 10 knife or cutter from passing into the sole of the boot or shoe after the heel has been trimmed, which would ruin the usefulness of the boot or shoe. Said bar u^5 is provided with a flattened portion u^8 and is held in its 15 adjusted position in the lug u^4 by means of a set-screw u^9 , and u^{10} is a lock-nut screwed upon the screw portion of said rod to prevent the loosening or slipping of the rod u or bar u^5 in said lug u^4 when the machine is in constant use.

The operation of the machine is as follows: After all the parts of the several pieces of mechanism hereinabove described are properly adjusted and the pulley-wheel c' operated 20 by means of a belt the foot-lever c^3 is operated to cause the clutch-collar d to come in operative holding contact with the hub of the wheel c' . A shoe with its heel portion in rough condition is placed upon the support 25 n^2 of the jack n with the heel portion between the arms a^{11} of the holding device a^{10} . The last heel-section is then placed upon the projecting ends of the nails in the unfinished heel, and the spanker h being operated, as 30 has been described, descends and securely fastens said heel-section upon the heel of the boot or shoe. The operation of the wrist-pin c^5 in the yoke i is such that when the said spanker-plate h is upon the heel, as illustrated 35 in Fig. 5, the cam projection d^4 on the sleeve d will tilt the lever r , and by means of the link o will cause the breaster-plate l to move down alongside the spanker-plate h in the guides therein and forcibly bring the blade 40 or knife down upon the inner edge of the heel, as clearly indicated in Fig. 6, to properly trim or breast said edge of the heel, as will be clearly understood. The stop bar or rod u^5 hereinabove mentioned is also brought 45 down, and its portion u^7 , coming in contact with the sole of the boot or shoe, will limit the cutting operation of the knife or cutter u to prevent injury to the sole of the shoe.

The springs m and p^8 serve to diminish the 50 force of the blows when the parts of the machine are in operation and act as suitable cushioning devices to reduce the wear and tear of the several parts and prevent any liability of the breaking of the parts.

55 By means of my present invention I have devised a simple and operative machine for

spanking and breasting heels for boots and shoes—that is, attaching the last heel-section to the heel portion and simultaneously trimming the inner edge of the heel.

70

Of course it will be evident that many changes may be made in the details of construction and general arrangements of the several parts of the machine herein set forth without departing from the scope of my invention. Hence I do not limit my invention to the exact arrangements and combinations of the parts herein shown and described.

75

Having thus described my invention, what I claim is—

80

1. In a spanking and breasting machine, the combination, with the frame of the machine, of a spanker and mechanism for causing a reciprocatory movement of said spanker, a breaster-plate having a knife or cutter, 85 and means for operating the same, after said spanker has attached the heel-section, a screw-threaded lug or ear on said knife or cutter, and a screw-threaded stop-bar adjustably arranged in said lug or ear to limit the combined downward-sliding motion of said knife or cutter and the breaster-plate, substantially as and for the purposes set forth.

90

2. In a spanking and breasting machine, the combination, with the frame of the machine, of a spanker and mechanism for causing a reciprocatory movement of said spanker, 95 consisting, essentially, of a main shaft, having a wrist-pin, and a yoke i operatively connected with said spanker, and a breaster-plate 100 having a knife or cutter, means for operating the same, after said spanker has attached the heel-section, a screw-threaded lug or ear on said knife or cutter, and a screw-threaded stop-bar adjustably arranged in said lug or 105 ear to limit the combined downward-sliding motion of said knife or cutter and the breaster-plate, substantially as and for the purposes set forth.

110

3. In a spanking and breasting machine, 110 the combination, with the frame of the machine, of a spanker and mechanism for causing a reciprocatory movement of said spanker, consisting, essentially, of a main shaft, having a wrist-pin, and a yoke i operatively connected with said spanker, and a breaster-plate 115 having a knife or cutter, and means for operating the same, after said spanker has attached the heel-section, consisting, essentially, of a pivoted lever r , a cam-sleeve on 120 the main shaft for operating the same, and a link connection between the free end of said lever and said breaster-plate, substantially as and for the purposes set forth.

120

4. In a combined heel spanking and breast- 125 ing machine, the combination, with the frame of the machine, of a spanker and mechanism for causing a vertical and reciprocatory movement of said spanker, and a breaster-plate operatively arranged to slide on the face of 130 said spanker and independently caused to move downward on said spanker after the

latter has attached the heel-section, substantially as and for the purposes set forth.

5. In a combined heel spanning and breasting machine, the combination, with the frame of the machine, of a spanker and mechanism for causing a vertical and reciprocatory movement of said spanker, guides on said spanker, a breaster-plate in said guides, and means for causing a reciprocatory motion of said breaster-plate in said guides, substantially as and for the purposes set forth.

6. The combination, with the frame A, of a shaft c and means for operating the same, a spanker-plate and means connected therewith and with said shaft for causing a vertical and reciprocatory movement of the spanker-plate, means connected therewith and operated from said shaft for causing a vertical and reciprocatory movement of said breaster-plate independent of and after the downward movement of the spanker-plate, a knife or cutter on said breaster-plate, and a spring-actuated jack, substantially as and for the purposes set forth.

7. The combination, with the frame A, of a shaft c, and means for operating the same, a spanker-plate having an opening, a yoke in said opening, and said yoke also having an opening with eccentric curves, a wrist-pin on said shaft c extending into said opening in said yoke and engaging with said eccentric curves, for causing a reciprocatory movement of said spanker-plate, and a breaster-plate operatively arranged to slide on the face of said spanker-plate and independently caused to move downward on said spanker-plate after the latter has attached the heel-section, substantially as and for the purposes set forth.

8. The combination, with the frame A, of a shaft c, and means for operating the same, a spanker-plate having an opening with eccentric curves, a wrist-pin on said shaft c extending into said opening in said yoke and engaging with said eccentric curves, for causing a reciprocatory movement of said spanker-plate, guides on said spanker-plate, a breaster-plate in said guides, and means for causing a reciprocatory motion of said breaster-plate in said guides, substantially as and for the purposes set forth.

50. 9. The combination, with the frame A, of a shaft c, and means for operating the same, a spanker-plate having an opening with eccentric curves, a wrist-pin on said shaft c extending into said opening in said yoke and engaging with said eccentric curves, for causing a reciprocatory movement of said spanker-plate, guides on said spanker-plate, a breaster-plate in said guides, and means for causing a reciprocatory motion of said breaster-plate in said guides, consisting, essentially, of a pivoted lever r, a cam-sleeve on the main shaft for operating the same, and a link connection between the free end of said lever and said breaster-plate, substantially as and for the purposes set forth.

65. 10. The combination, with the frame A, of a shaft c and means for operating the same, of

a sleeve d having a cam surface or projection d⁴, a pivoted lever r adapted to be actuated by said sleeve, said lever having a socket end 70 r', a block therein, a link connected therewith, a reciprocatory breaster-plate also connected with said link, and having a knife or cutter, substantially as and for the purposes set forth.

75. 11. The combination, with a spanker-plate h having an opening h², of a yoke i in said opening, said yoke having an opening i' with eccentric curves i², i³ and i⁴, an operating-shaft, and a wrist-pin on said shaft extending 80 into said opening i', substantially as and for the purposes set forth.

12. The combination, with a spanker-plate h, having guides h³, of a breaster-plate l arranged on said plate h, and a cutter or knife 85 on said breaster-plate, substantially as and for the purposes set forth.

13. The combination, with a reciprocally-moving breaster-plate l, of a cutter or knife u, adjustably secured to said plate, a screw-threaded lug or ear on said knife or cutter, and a screw-threaded stop-bar u⁵ adjustably arranged in said lug or ear of said knife or cutter, substantially as and for the purposes set forth.

95. 14. The combination, with a reciprocally-moving breaster-plate l, of a cutter or knife u, adjustably secured to said plate, a perforated lug u⁴ on said knife or cutter, a screw-threaded stop-bar in said perforated lug, having a flat surface u⁸, a set-screw u⁹, and a lock-nut, all substantially as and for the purposes set forth.

15. In combination, with the standard A, a shoe-supporting jack, a bracket on said standard, a bearing a⁹ on said bracket, a spring-actuated set-screw in said bearing, and a spring-support a¹⁰ connected with said screw, substantially as and for the purposes set forth.

110. 16. In a machine of the character set forth, in combination, the standard A, a bracket on said standard, a bearing a⁹ on said bracket, a spring-actuated set-screw in said bearing, a spring-support a¹⁰ connected with said screw, the table b of said standard, a bearing k², a 115 screw-threaded ring k⁴ and screw-threaded boss in said ring, said boss having a chambered portion k⁸, a spring therein, and a jack, substantially as and for the purposes set forth.

120. 17. In a machine of the character set forth, the combination, with the standard A, a shaft c, and a clutch-collar d, of a lever r fulcrumed in a support on said standard, a roller on one end of said lever in engagement with said collar d, a frame t connected with the machine-frame, a spring r³ connecting the other end of said lever with said frame t, and a heel-trimming knife or cutter operatively connected with said lever, substantially as and for the purposes set forth.

125. 18. In a machine of the character set forth, the combination, with the standard A, a shaft c, and a clutch-collar d, a cam-shaped projection d⁴ on said collar, a lever r fulcrumed

in a support on said standard, a roller on one end of said lever in engagement with said collar d , a frame t connected with the machine-frame, a spring r^3 connecting the other end 5 of said lever with the frame t , and a heel-trimming knife or cutter operatively connected with said lever, substantially as and for the purposes set forth.

In testimony that I claim the invention set forth above I have hereunto set my hand this 30th day of March, 1897.

WILLIAM HIGGINS.
